UNITED STATES PATENT OFFICE.

JOHN H. KNAUFT, OF MILWAUKEE, WISCONSIN.

DESK FOR BOOKKEEPING-MACHINES, &c.

1,384,530.

Specification of Letters Patent. Patented July 12, 1921.

Application filed March 15, 1920. Serial No. 365,751.

To all whom it may concern:

Be it known that I, JOHN H. KNAUFT, a citizen of the United States, residing at Milwaukee, in the county of Milwaukee and 5 State of Wisconsin, have invented certain new and useful Improvements in Desks for Bookkeeping-Machines, &c., of which the following is a specification, reference being had to the accompanying drawing, forming 10 a part thereof.

This invention relates to desks for book-keeping machines, etc., and the object of the invention is to improve the construction of 15 desks in the manner to be hereinafter de-scribed and claimed.

Referring to the drawings which accom-pany this specification and form a part here-of, which drawings illustrate an embodiment 20 of this invention, and on which drawings the same reference characters are used to 25 designate the same parts wherever they may appear in each of the views, Figure 1 is a vertical, transverse section of the desk on the line 1—1 on Fig. 2, looking in the di-rection indicated by the arrows; and Fig. 25 is a front elevation of the desk.

Referring to the drawings, the reference numerals 1 and 2 designate end members 30 which may be constructed in any suitable or preferred manner and which are con-nected in any suitable manner as, for ex-35 ample, by a back 3 and a bar 4 to form a rigid structure. A top 5 is pivotally con-nected with a pair of links at each end and 40 the links of each pair of links are designated by the reference numerals 6 and 7. The drawings illustrate the links 7 as pivoted to the ends of the desk by pivots 8 which are located below and to the rear of the pivots 45 9 by which the links 6 are pivoted to the ends of the desk. In other words, the links 6 and 7 are pivoted non-concentrically to the ends of the desk in such a manner that the rear and the front edges of the top move in 50 arcs of different circles when the top is be-55 ing turned from a horizontal to a vertical position or vice versa, as is clearly shown by Fig. 1 of the drawings. This construction enables the top to be moved bodily to the rear on the latter part of its opening movement as distinguished from a circular 55 rotation. The links 7 are provided with counterweights 10 on the opposite sides of their pivots 8 from the top 5 and these counterweights not only partly counter-balance the weight of the top 5 when it is being

moved from one position to another but also hold the top 5 firm and steady upon the supports 11 when the top is in its horizontal position. The horizontal position for the 60 top is preferred when the top is closed so that papers will not slide from it but the invention is not limited to a horizontal po-sition of the top.

The back 3 is provided with a stop 12 with 65 which a stop 13 projecting from the top 5, is adapted to engage. These stops may be formed in any suitable manner. The stop 12 is illustrated by the drawings as a metal plate extending the length of the top of the 70 desk and the stop 13 is illustrated by the drawings as a metal plate extending sub-stantially the length of the top of the desk 75 to make a tight joint to prevent papers from slipping through between the back 3 and the top 5. In all constructions of ordi-nary manufacture in which pivoted con-nections are employed, there is a little loose-ness or play between the parts and the stop 13 on the top 5 is held in close contact with 80 the stop 12 on the back 3 by the counter-weights 10, and the stop 12 prevents the top 5 from moving forward on the steady-ing supports 11.

When the top 5 is moved from its closed, 85 horizontal position to its opened, vertical position, as shown by Fig. 1 of the draw-ings, the top rests against and is supported by the bar or stop 4, it being understood, of course, that the counterweights 10 are not 90 of sufficient power to lift the top from the bar 4.

The reference numeral 14 designates a bar or stop against which a bookkeeping ma-chine, not shown, for example, may abut to 95 position the machine properly with respect to the desk.

The use and operation of the desk will be readily understood from the foregoing de-scription and from an inspection of the 100 drawings. In opening the top of the desk, the movement of the top requires but very little space so that desks may be placed compactly within a limited area. When the top of the desk is closed, it affords an 105 exceptionally firm and immovable desk sur-face, and when the top of the desk is opened, the top forms a vision shield to prevent dis-traction or annoyance.

What is claimed is:

1. The combination in a desk of ends, a back, a movable top adapted to be moved

- from a substantially horizontal position to a substantially vertical position, or vice versa, a plurality of links pivoted non-concentrically on each end of the desk and pivoted to 5 the top of the desk, stops for limiting the movements of the top of the desk, and counterbalance mechanism connected with the top in such a manner as to leave the space between the ends substantially unobstructed.
- 10 2. The combination in a desk of ends, a back, a movable top adapted to be moved from a substantially horizontal position to a substantially vertical position, or vice versa, a plurality of links pivoted non-concentrically on each end of the desk and pivoted to the top of the desk, some of the links being provided with counterbalance weights near the ends of the desk to leave the space between the ends substantially unobstructed,
- 15 20 a bar connecting the ends and serving as a stop for the top when in its vertical position, means for supporting the top when in its substantially horizontal position, and means to serve as a stop and to make a tight joint 25 between the top and the back.
3. The combination in a desk of ends rigidly connected together only at their rear

sides to leave an unobstructed space between the ends and their connection, a top movably supported by links pivoted to the ends and to the top, means to support the top in a substantially vertical position, and means to support the top in a substantially horizontal position.

4. The combination in a desk of two ends, 35 a back connecting the ends, a bar connecting the ends and spaced below the back to permit a top to be swung therebetween so as to rest in a substantially vertical position on the bar, links pivotally connected with the front 40 part of the top and with the ends, links pivotally connected with the back part of the top and with the ends non-concentrically with the first mentioned links and provided with counterbalance weights, supports for 45 the top when in a substantially horizontal position, said top, the said counterbalance weights tending to move the top upon said supports forward and away from the back, and a stop to limit the extent of such movement.

In witness whereof I hereto affix my signature.

JOHN H. KNAUFT.
